UNITED STATES PATENT OFFICE

109,190

DESIGN FOR KNITTED FABRIC

David Siegel, New York, N. Y.

Application February 28, 1938, Serial No. 75,449

Term of patent 7 years

To all whom it may concern:

Be it known that I, David Siegel, a citizen of the United States, residing at New York city, in the county and State of New York, have invented a new, original, and ornamental Design for Knitted Fabric, of which the following is a specification, reference being had to the accompanying drawing forming a part thereof, wherein the single figure illustrates on an enlarged scale, an area of fabric embodying said design.

I claim:

The ornamental design for knitted fabric, substantially as shown.

DAVID SIEGEL.
